UNITED STATES PATENT OFFICE.

THOMAS SMITH, OF MEADVILLE, PENNSYLVANIA.

ROD-PACKING.

1,338,163.

Specification of Letters Patent. Patented Apr. 27, 1920.

Application filed August 28, 1917. Serial No. 188,632.

To all whom it may concern:

Be it known that I, THOMAS SMITH, a citizen of the United States, residing at Meadville, in the county of Crawford and State 5 of Pennsylvania, have invented a new and useful Rod-Pack, of which the following is a specification.

The device forming the subject matter of this application is a rod packing, adapted 10 especially for use on piston rods of locomotive engines, on valve stems and the like.

The invention aims to provide novel means for holding the parts of the segmental packing rings in place with respect 15 to each other and with respect to a cup wherein the rings are disposed.

Another object of the invention is to provide novel means whereby the parts of the rings will be prevented from moving outwardly against the wall of the cup, the construction being such that the pressure at all 20 times will be effective to set up the rings on the rod.

It is within the province of the disclosure 25 to improve generally and to enhance the utility of devices of that type to which the present invention appertains.

With the above and other objects in view which will appear as the description proceeds, the invention resides in the combination 30 and arrangement of parts and in the details of construction hereinafter described and claimed, it being understood that changes in the precise embodiment of the invention herein disclosed can be made within 35 the scope of what is claimed, without departing from the spirit of the invention.

In the accompanying drawings:—

Figure 1 shows in front elevation, a portion 40 of the cylinder of a locomotive engine, whereunto the device forming the subject matter of this application has been applied, the piston rod appearing in section;

Fig. 2 is a section taken approximately on 45 the line 2—2 of Fig. 1, the piston rod appearing in elevation;

Fig. 3 is a section on the line 3—3 of Fig. 2;

Fig. 4 is a section on the line 4—4 of 50 Fig. 2;

Figs. 5 and 6 are transverse sectional views showing modified forms of the invention;

Figs. 7, 9 and 11 are top plans showing 55 modifications in certain of the rings;

Figs. 8, 10 and 12 are elevations of the

structures shown, respectively, in Figs. 7, 9 and 11.

Referring to that form of the invention which is disclosed in Figs. 1 to 4, both inclusive, the numeral 1 denotes a cylinder head provided with a stuffing box 2 coöperating with a gland 3 held to the stuffing box 2 by means of bolts 4. The rear face of the gland 3 is provided with an annular recess 5 receiving a copper wire 6 or the like, pressed against the forward end of the stuffing box 2 to form a packing. The gland 3 has an annular, rearwardly projecting rib 7. A lubricator case 8 is held by certain of the bolts 4 to the gland 3 and in the lubricator case is slidably mounted a receptacle 9 having an outlet 10, the numeral 11 marking any suitable source of oil supply for the receptacle. The receptacle 9 is curved as 75 shown at 12 to coöperate with a piston rod 14 having an enlarged end 15. Any suitable lubricating means may be provided, however.

The gland 3 is supplied with an opening 16 80 through which the piston rod 14 passes, this opening being slightly greater in diameter than the enlarged end 15 of the piston rod 14. In the cylinder head 1 is fashioned an opening 17 which, like the opening 16, is 85 slightly larger in diameter than the end 15 of the piston rod 14. The stuffing box 2 is provided with a chamber 18 defining a shoulder 19 adjacent the opening 17.

Disposed within the chamber 18 and surrounding the piston rod 14 is a cup 20 which abuts with a ground joint against the rib 7 of the gland 3. The cup 20 has a tapered opening 21 in which fits a tapered, two-part bushing 22, the constituent members of 95 which may be united by means of dowel pins 23. The bushing 22 is supplied adjacent its rear end with a flange 24 received in a correspondingly shaped recess formed in the cup 20. The wall of the cup 20 is provided 100 in its interior, as shown in Figs. 3 and 4, with grooves 25, 26, 27 and 28. The bushing 22 may be of various forms, without jeopardizing the utility of the invention, and if the piston rod 14 does not have the enlarged 105 end 15, then the bushing 22 may be omitted entirely.

Disposed within the cup 20 and abutting against the bushing 22 is a forward ring comprising a part 29 and a smaller part 30, 110 the forward ring being spaced as indicated at 31 from the inner surface of the cup 20.

The part 29 of the ring has lugs 32 received in the grooves 26 and 25 of the cup 20, the part 30 of the forward ring having a lug 33 which is received in the groove 28 of the cup. Near to its ends the part 29 of the forward ring is supplied with recesses 34 in which the ends of the part 30 of the ring are slidably received, the parts of the ring, at their ends, having flat, slidably coöperating faces shown at 35.

Disposed within the cup 20, about the piston rod 14, and abutting against the forward ring, is a rear ring, comprising parts 36 and 37. The part 36 of the rear ring is provided with lugs 38 received in the grooves 27 and 28, the part 37 of the rear ring being equipped with lugs 39 received in the grooves 25 and 26. The ends of the parts 36 and 37 of the rear ring are spaced as shown at 40. It is to be observed that owing to the way in which the ribs on the forward and rear rings coact with the grooves in the cup, the spaces 40 between the parts 36 and 37 of the rear ring will be maintained out of alinement with the spaces 34 between the parts 29 and 30 of the forward ring, so that there will be no leakage of pressure. As clearly shown in Fig. 2, the parts 36 and 37 of the rear ring are beveled 30 inwardly and rearwardly, as indicated at 41.

The piston rod 14 is surrounded by a retaining ring 42 including a flange 43 against which abuts one end of a compression spring 44, the other end of the compression spring 35 abutting against the shoulder 19. The spring 44 surrounds the ring 42 (which is made in two parts) and holds the parts together. As shown at 45, the retaining ring 42 is beveled outwardly and forwardly, to 40 coöperate with the beveled surface 41 of the rear ring. This construction prevents the rear ring from moving outwardly, into contact with the wall of the cup 20, and as a consequence, pressure can always find its 45 way about the forward and rear rings, to set the same up snugly on the piston rod 14.

It is not necessary that the ring 42 be held about the rod 14 by the action of the spring 44 alone. In Fig. 6 of the drawings, the numeral 46 marks the piston, the two-part retaining ring is shown at 47, and the spring appears at 48. In this form of the invention, the constituent members of the retaining ring 47 are held by a continuous ring 49 50 against outward radial movement.

In Fig. 5 of the drawings, the cup is shown at 50 and the grooves appear at 51.

The numeral 56 marks the piston rod. The ring is made up of like parts 52, having lugs 53 coöperating with the grooves 51. In one 60 end of each ring part 52 there is fashioned a recess 54 receiving the thinned end 55 of the other ring part.

In Figs. 7 and 8 of the drawings, one part 57 of the ring is of considerably greater circumferential extent than the other part 58 thereof, the parts 57 and 58 of the ring being halved together slidably as shown at 59, the beveling of the ring appearing at 60, and the lugs being shown at 61.

In Figs. 9 and 10, the parts of the ring are shown at 62 and are of like construction, so far as circumferential extent is concerned, the parts 62 of the ring being halved together as shown at 63, the ring being beveled 75 as shown at 64. The numeral 65 marks the lugs on the ring.

In Figs. 11 and 12, the parts 66 of the ring are halved together as shown at 67 and are beveled as indicated at 68, the ends of the 80 parts of the ring being rounded off, if desired, as shown at 69. In this form of the invention, the ring is devoid of lugs, and when such a ring as that shown in Figs. 11 and 12 is used, the cup will be devoid of 85 the grooves hereinbefore described.

Figs. 7, 8, 9 and 10 indicate that the specific form of ring employed may be varied from the showing of Figs. 3 and 4.

Having thus described the invention, 90 what is claimed is:—

In a device of the class described, a stuffing box; a gland constituting a closure therefor; a cup abutting against the gland; a segmental forward ring in the cup; a segmental rear ring in the cup and having an inwardly and rearwardly beveled end face; a retaining ring having a beveled face coöperating with the beveled face of the rear ring to prevent the latter from expanding 100 outwardly against the cup; spring means for advancing the retaining ring; interengaging elements on the cup and the segmental rings coacting to render the forward ring responsive to thrust and radial movement, only, 105 derived from the rear ring; and a rod working in the rings.

In testimony that I claim the foregoing as my own, I have hereto affixed my signature in the presence of two witnesses.

THOMAS SMITH.
